OIL DRIP SUMP AND VAPORIZER FOR
OIL BURNERS

Charles V. Copeland, Fort Wayne, Ind., assignor to Wayne Home Equipment Co., Inc., Fort Wayne, Ind., a corporation of Indiana

Filed July 15, 1965, Ser. No. 472,193
4 Claims. (Cl. 239—121)

This invention relates generally to gun-type oil burners, and more particularly to novel means for collecting and vaporizing the oil which may drip from the nozzle following shut-down of the burner.

Conventional domestic gun-type oil burners, such as those employed for firing home furnaces, commonly comprise a blower for supplying combustion air, a cylindrical blast tube connected to the blower, an air cone secured to the front end of the blast tube, an oil pump commonly driven by the same motor as the blower, an oil line coupled to the pump and extending axially through the blast tube, a nozzle connected to the front end of the oil line within the blast tube and adjacent the front end thereof, an ignition transformer, and ignition electrodes also positioned in the blast tube adjacent the nozzle and connected to the transformer. Such gun-type oil burners are installed with the blast tube extending into the combustion chamber of the furnace. When such a conventional oil burner is shut down, and the pressure provided by the pump is thus removed from the oil line and nozzle, a small quantity of oil will remain in the nozzle. Due to the ambient heat remaining in the region of the nozzle immediately following shut-down of the oil burner, the oil remaining in the nozzle will expand, thus causing a few drops of oil to ooze out of the nozzle which drip down onto the air cone. The underwriters have required the provision of an oil drain hole at the bottom of the air cone in order to drain this oil into the combustion chamber where it is vaporized. However, there are instances where, either through initial installation of the oil burner or some subsequent cause, the blast tube is inclined downwardly from the front end toward its rear end. In such instances, the oil which drips out of the nozzle following shut-down of the burner may drain down the blast tube rather than through the oil drain hole in the air cone. In the case of an oil burner having a relatively long blast tube, the few drops of oil which thus drain rearwardly down the blast tube may be completely vaporized by the latent heat remaining in the blast tube. However, in the case of oil burners having a short blast tube, some of this oil may drain out of the rear end of the blast tube, thus giving the appearance of an oil leak. This oil which drains down and out of the blast tube following each shut-down of the burner not only is hazardous, but has created an illusive and frustrating problem for the service man; the inclination of the blast tube which causes this drainage may be hardly perceptible and thus the service man tends to spend an undue amount of time searching for the cause of a nonexistent oil leak.

It is, therefore, desirable to provide means for collecting and retaining any oil drip which tends to drain rearwardly down the blast tube so it may be vaporized. It is further desirable that such means be readily installed on existing as well as newly constructed oil burners and that it be characterized by its simplicity, ease of installation, and low cost.

It is accordingly an object of the invention to provide improved means for collecting and vaporizing oil which drips from the nozzle of a gun-type oil burner following shut-down and which may tend to drain rearwardly down the blast tube.

2

In accordance with the invention, an oil sump and vaporizer member is provided formed of relatively thin high heat-conductive metal. This member has front and rear ends and opposite side edges and is formed to be arcuate between its side edges so as to conform to the inner surface of a cylindrical blast tube. The member is positioned in the blast tube engaging the inner surface of the bottom portion thereof with its front end adjacent the front end of the blast tube and extending rearwardly from the air cone toward the rear end of the blast tube. The member has a transverse wall formed at its rear end extending between the side edges so as to form a dam for collecting and vaporizing any oil drip which may tend to drain rearwardly down the blast tube.

The above-mentioned and other features and objects of this invention and the manner of attaining them will become more apparent and the invention itself will be best understood by reference to the following description of an embodiment of the invention taken in conjunction with the accompanying drawings, wherein:

FIG. 1 is a fragmentary side cross-sectional view showing the blast tube, air cone, nozzle and electrode assembly of a conventional oil burner equipped with the oil sump and vaporizer member of the invention;

FIG. 2 is a cross-sectional view taken along the line 2—2 of FIG. 1;

FIG. 3 is a view in perspective of the oil sump and vaporizer member of the invention; and

FIG. 4 is a front end view of the oil sump and vaporizer member of FIG. 3.

Referring now to the figures of the drawing, there is shown a conventional cylindrical metal blast tube 10 of a conventional gun-type oil burner having its rear end 12 adapted to be connected to the blower housing (not shown) for delivering combustion air to the blast tube as is well known to those skilled in the art. A conventional air cone 14 is provided secured to the front end 16 of the blast tube 10 in any suitable manner, as by screw 18; in the illustrated embodiment, air cone 14 has a cylindrical surface 20 which is received within the blast tube 10 and a shoulder 22 extending radially outwardly from surface 20 to form a rabbet connection with the front end 16 of the blast tube 10. Air cone 14 has a front opening 24 through which the flame and the combustion air is projected into the combustion chamber of the furnace. It will be readily understood that the forward portion of the blast tube 10 and the air cone 14 extend into the combustion chamber. Air cone 14 may be provided with conventional vanes 26 for imparting a swirling motion to the combustion air.

A conventional oil line 28 extends axially through the blast tube 10 having its rear end 30 coupled in conventional fashion to the oil pump (not shown). A conventional nozzle adaptor 32 is threaded onto the front end 34 of oil line 28 and in turn has a conventional nozzle 36 threaded therein, nozzle 36 extending into the air cone 14, as shown. A pair of conventional ignition electrodes 38, 40 are provided disposed adjacent nozzle 36 and respectively supported by conventional electrode insulators 42, 44 which also extend axially in the blast tube 10. Electrodes 38, 40 are suitably connected to the ignition transformer (not shown) of the oil burner by bus bars 46, 48. Oil line 28 with the nozzle adaptor 32 and nozzle 36 connected thereto and the ignition electrode insulators 42, 44 are conventionally supported within the blast tube 10 by air stabilizer 50 which engages spaced points on the inner surface 52 of blast tube 10 and which may also have suitable vanes 54 thereon for imparting an initial swirling motion to the combustion air.

As above-described, when the oil burner is shut down,

thus terminating operation of the pump connected to the oil line 28, a small quantity of oil will remain in the oil line 28, nozzle adaptor 32 and nozzle 36. Due to the latent heat of the component parts and the ambient heat within the combustion chamber remaining immediately following shut-down of the oil burner, this small quantity of oil will be caused to expand, thus causing a few drops of oil to ooze out of the nozzle orifice 56 and drop onto the inner surface 58 of the air cone 14. In order normally to drain these few drops of oil into the combustion chamber for vaporization, air cone 14 is provided with a drain hole 60 at the bottom as shown.

It will be readily understood that the blast tube, air cone, nozzle and electrode structure thus far described is conventional and does not form a part of the present invention other than in combination with the novel oil sump and vaporizer member now to be described.

In accordance with the invention, an oil sump and vaporizer member 62 is provided integrally formed of thin-gauge high heat-conductive metal, preferably aluminum. Member 62 has rear and front ends 64, 66 and side edges 68, 70 and is arcuately formed between the side edges 68, 70 so as to conform to the curvature of the inner surface 52 of the blast tube 10. Member 62 has a transverse wall 72 formed at its rear end 64 extending between side edges 68, 70 and an out-turned flange 74 formed at its front end 66. Member 62 is positioned within blast tube 10 in engagement with the inner surface 52 thereof with flange 74 overhanging front end 16, member 62 thus being secured between the inner surface 52 of blast tube 10 and the outer cylindrical surface 20 of air cone 14 and flange 74 being secured between end 16 and shoulder 22 of air cone 14. The rear portion 76 of member 62 terminating in the wall 72 thus extends rearwardly from the rear end 78 of air cone 14, as best seen in FIG. 1.

It will now be seen that the transverse wall 72 of the member 62 forms a dam so that if the blast tube 10 is inclined downwardly from its front end 16 to its rear end 12, any oil which drips from orifice 56 of nozzle 36 onto the inner surface 58 of air cone 14 following shutdown of the burner and which thus tends to drain down the blast tube 10 toward the rear end 12 thereof will be collected and retained in the exposed portion 76 of member 62 where it will be vaporized by the latent heat remaining in blast tube 10 and in member 62.

Since member 62 is formed of thin gauge metal, it will be seen that it may be initially placed on the inner surface 52 of blast tube 10 with flange 74 overhanging end 16 and the air cone 14 then assembled onto the end 16 of the blast tube, engagement of the cylindrical surface 20 of the air cone 14 with the member 62 thus insuring heat-transferring engagement of the member 62 with the inner surface 52 of the blast tube 10. It will further be seen that the oil sump and vaporizer member 62 of the invention may be inexpensively formed in a simple press operation and that it may readily be installed by an ordinary service man on existing burners in the field, no special tools being required for such installation; the

member 62 may be installed with equal facility during initial assembly of the oil burner at the factory.

While there have been described above the principles of this invention in connection with specific apparatus, it is to be clearly understood that this description is made only by way of example and not as a limitation to the scope of the invention.

What is claimed is:

1. In a gun-type oil burner including a source of combustion air, a cylindrical blast tube adapted to extend into a combustion chamber and having its rear end communicating with said air source, an air cone secured to the front end of said blast tube, a source of oil under pressure, an oil line extending axially through said blast tube and having its rear end connected to said oil source, and a nozzle within said blast tube adjacent said front end thereof and connected to the front end of said oil line, said air cone having an oil drainage opening formed in the bottom thereof for draining oil into said combustion chamber which may drip from said nozzle following shut-down of said oil burner; the combination with said blast tube and air cone of an oil sump and vaporizer member formed of relatively thin high heat-conductive metal, said member having front and rear ends and opposite side edges, said member being arcuate between said side edges and conforming to the inner surface of said blast tube, said member being positioned in said blast tube engaging the inner surface of the bottom portion thereof with its front end adjacent the front end of said blast tube, said member extending rearwardly from said air cone toward said rear end of said blast tube, said member having a transverse wall formed at said rear end extending between said side edges thereby forming a dam for collecting and vaporizing said oil drip which may drain rearwardly in said blast tube.
2. The combination of claim 1 wherein said member has an out-turned flange formed at its front end, said flange overhanging said front end of said blast tube.
3. The combination of claim 1 wherein said air cone has a cylindrical portion which is received within said blast tube engaging the inner surface thereof, and wherein in said member is secured between said air cone cylindrical portion and said inner surface of said blast tube.
4. The combination of claim 1 wherein said air cone has a cylindrical portion which is received within said blast tube engaging the inner surface thereof and a shoulder extending radially outwardly from said cylindrical portion forming a rabbet connection with said front end of said blast tube, said member being integrally formed of thin gauge aluminum and having an outturned flange formed at its front end, said member being secured between said air cone cylindrical portion and said inner surface of said blast tube, and wherein said flange overhangs said front end of said blast tube and is secured between the same and said air cone shoulder.
